ABSTRACT OF THE DISCLOSURE

An entry table structure for supporting flat strip stock as it enters the entry end of a tube mill for forming from a continuous flat strip of metal, a tube of a predetermined selected diameter wherein the table includes means for effecting vertical movement of one end thereof with respect to the other.

The present invention relates to a method and apparatus for forming from a continuous flat strip of metal, a tube of predetermined selected diameter. More particularly, the invention relates to the entry end of a tube mill wherein the forming operations of the flat strip stock are initially commenced.

In recent years the production rates of tube mill equipment have steadily increased. Previously, tube mills having production capacities of the order of 60 to 120 feet per minute were considered acceptable; however, today it is not uncommon to be confronted with the requirement of 150 to 300 feet per minute. Such high production rates have caused many problems in the handling of the material being formed. In addition to the problems caused by the higher production rate requirements, recently developed concepts have made it possible for a single mill to produce tubing of a large range of diameters from stock of a large range of wall thickness.

It is an object of the present invention to produce a tube mill having a universal entry end section adaptable to receive flat strip stock used for forming tubing of a predetermined diameter selected from a wide range.

Another object of the invention is the production of a tube mill having an entry end section capable of being readily adjusted to accommodate flat strip stock of a thickness selected from a wide range.

These and other objects and advantages of the invention will become apparent from the following detailed description of an embodiment of the invention when considered together with the accompanying drawings in which:

FIGURE 1 is a fragmentary perspective view of a tube mill illustrating the entry end of the forming section thereof;

FIGURE 2 is a fragmentary elevational view of the tube mill section, illustrated in FIGURE 1;

FIGURE 3 is an end elevation of the apparatus illustrated in FIGURES 1 and 2, taken opposite to the direction of the strip travel; and

FIGURE 4 is a top plan view of the apparatus illustrated in FIGURES 1, 2, and 3.

Referring to the drawings, there is illustrated the initial portion of the forming section of a tube mill, generally referred to as the "entry end" of the mill. In the apparatus illustrated, there is provided a plurality of sequentially arranged supporting rolls 10 and sets of forming rolls 12 and 13. These rolls are rotatably mounted on a base frame consisting typically of a pair of parallel, spaced apart side rail members 14 and 16; and parallel spaced apart end rail members 18 and 20.

The opposite ends of the individual rolls 10 which form the support rolls are rotatably journaled within bearing elements 22 and 24 secured to the upper portion of the side rail members 14 and 16, respectively. The forming rolls 12 and 13, which comprise the forming section, are

2

typically arranged in sets of individual rolls such that the side rolls 12 have their rotational axes inclined toward one another, whereby the imaginary extensions thereof form an obtuse angle. The intermediate supporting rolls 13 are disposed to rotate about generally horizontally disposed axes and are generally co-planar with respect to the rolls 10. The innermost ends of the rolls 12 are rotatably journaled within bearing elements 26 supported by a respective one of a pair of spaced, centrally disposed rail members 28 and 30. One end of each of the rail members 28 and 30 is secured to the end rail member 18; while the opposite end of each is secured to a transversely extending rail member 32.

The outer ends of the forming rolls 12 are rotatably journaled within bearing elements 34 which are arranged to position the rolls 12 such that the inclination thereof becomes greater in the direction of travel of the strip of metal being formed. The direction of travel of the strip being formed is from right to left in FIGURES 1, 2, and 4.

Between each pair of forming rolls 12 there is disposed a generally horizontally disposed supporting roll 13. The opposite ends of each of the supporting rolls 13 are rotatably journaled within bearing elements 36 and 38 which in turn are secured to the centrally disposed rail members 28 and 30, respectively. At the right hand, or inlet, side of the apparatus, there is disposed a pair of spaced apart upstanding standards 40 and 42 arranged to rotatably support the opposite ends of one roll 44 of a pinch roll assembly. In the arrangement illustrated, the roll 44 is disposed immediately above a supporting roll 10 which cooperates therewith to provide the pinch roll assembly. Since each of the standards 40 and 42 is identical with the other, only a single one will be described in detail herein for the sake of simplicity. The standard 42 is provided with a vertically extending slot 46 which slidably receives bearing element 48 for rotatably supporting the respective end of the roll 44. The bearing element 48 is retained within the slot 46 and may be adjusted vertically by a threaded adjustment device 50. It will be appreciated that by turning the threaded adjustment device 50 in one direction, the respective end of the roll 44 will be lowered; while turning the device in an opposite direction will cause the end to be elevated.

The edges of the strip of metal stock being formed are guided between pairs of horizontally spaced apart guide rolls 52 and 54. The guide rolls 52 and 54 are mounted in supporting assemblies enabling the rolls to be adjusted horizontally toward and away from one another simultaneously; or alternatively, the rolls may be moved horizontally independently of one another. Each of the assemblies includes a bearing yoke for rotatively journaling each guide roll, a slide member for each bearing yoke, a way for slidably supporting the slide members, and means for effecting relative movement of the members with respect to one another. For the sake of simplicity, a description of the mechanism for adjusting the roll 52 will be made in detail, since the mechanism for the other roll 54 of the assembly is identical therewith.

The guide roll 52 is journaled within a bearing yoke 56 to rotate about a vertical axis. The bearing yoke 56 is in turn fixedly secured to a slide member 58, which is slidably mounted in a way 60 extending transversely of and spanning the space between the side rail members 14 and 16. The slide member 58 may be moved along the way 60 by an externally threaded drive screw 62, which is received within an internally threaded bore which extends through the slide member 58.

The outermost end of the drive screw 62 is supported by a bearing element 64 which is mounted in the end wall of the way 60. A portion of the drive screw 62 is adapted to extend through the bearing 64 and is formed to receive

a hand crank, or the like, for imparting rotational movement thereto for effecting adjustment of the guide roll 52. The innermost end of the drive screw 62 is connected to a coupling 66, which is likewise coupled to the corresponding innermost end of a threaded drive screw for controlling the guide roll 54.

The coupling 66 is of the type which can be uncoupled, allowing the respective drive screws to rotate independently of one another, enabling one or the other of the guide rolls 52 and 54 to be adjusted independently. However, when the coupling 66 is in its coupled condition, simultaneous inward or outward movement of the guide rolls 52 and 54 can be effected depending merely on direction in which the drive screw 62 is turned.

In the embodiment illustrated, there are three guide roll assemblies; however, it will be readily appreciated that more or less in number may be employed, depending primarily on the length of the mill section.

The initial bending or forming of the strip of metal stock is accomplished by the interaction of the forming rolls 12, 13 and a relatively large roll 70. The roll 70 is rotatably mounted within a generally inverted U-shaped frame 72 and is adapted to rotate about a horizontal axis in parallel spaced relation above the axes of rotation of the rolls 13. The opposite ends of the frame 72 may be suitably secured to the respective side rail members 14 and 16. As the metal strip is directed along the supporting rolls 10 and thence across the forming rolls 12, 13, the leading edge thereof is caused to pass between the lower tangential surface of the roller of the roll 70 and the upper tangential surfaces of the cooperating rolls 12 and 13, causing the strip of metal to be progressively converted into a shallow U-shaped cross-sectional form prior to its entry into the main forming section of the mill.

The main forming section of the mill is comprised of a plurality of forming rolls which progressively convert the metal strip into substantially tubular form. The initial set of forming rolls, as shown on the accompanying drawings, comprises a lower roll 80 and a cooperating upper roll 82, each of which is adapted to rotate about a horizontal axis. The rolls 80 and 82 are rotatively mounted within a pair of spaced apart upstanding standards 84 and 86. It will be readily apparent that, where different strip thicknesses are employed, the angle of entry of the strip from the entry end of the mill into the forming section will vary. In order to accommodate for the desired angular entry of the strip, the entry end of the mill is adjustably supported. More particularly, the end of the entry end containing a pinch roll assembly is pivotally mounted to a base element 90. The base element 90 contains a pair of spaced apart outwardly extending bracket members 92 and 94 which are pivotally connected to downwardly extending brackets 96 and 98, respectively, which are fixedly secured to the end rail member 20.

The opposite end of the entry end of the mill is provided with mechanism for raising and lowering the entire section to pivot about the elements 92, 94, 96 and 98. The mechanism comprises a base member 100, having a pair of spaced apart upwardly extending brackets 102 and 104, which pivotally contain lower ends of a pair of rack members 106 and 108, respectively. The rack members 106 and 108 are mounted within the respective brackets 102 and 104 in such a manner that a limited amount of relative pivotal movement is permitted between the rack members and their respective brackets.

A pair of downwardly depending spaced apart bearing elements 110 and 112 is fixedly secured to a transversely extending rail member 114. The opposite ends of the rail member 114 are secured to the side rails 14 and 16 of the main frame. A set of pinions 116 and 118 are keyed, or otherwise fixedly secured, to the opposite ends of a shaft 120, which, in turn, is rotatively mounted within the bearing elements 110 and 112. The pinions 116 and 118 cooperate and mesh with the teeth of the respective rack members 106 and 108 to provide for proper align-

ment of the main frame during any upward or downward movement, as will be explained in detail hereinafter.

Intermediate the brackets 102 and 104, there is disposed another similar upwardly extending bracket 122, which is fixedly secured to the base 100. The bracket 122 is pivotally connected to the bottom end of a pressure fluid actuated piston and cylinder mechanism 124 having suitable inlet and outlet connections communicating with a source of pressure fluid, not shown. The upper end of the mechanism 124 is pivotally connected to a bracket 126 which in turn is fixedly secured to a transversely extending rail member 128. The respective ends of the rail member 128 are secured to the side rails 14 and 16.

In operation, it will be readily apparent that the one end of the base frame of the entry end of the mill may be elevated or lowered by the introduction or release of pressure fluid into or out of the pressure fluid actuated piston and cylindrical mechanism 124. The rack and pinion assembly, as will be appreciated, is employed to assure that proper alignment of the base frame is maintained during the raising or lowering of the frame.

The forming roll 70 preforms the strip of metal stock prior to entering the main forming section of the mill and thereby enables the strip to be fed into the forming section at a speed equal to the speed of the mill without damage to the strip or the subsequent forming rolls.

The apparatus described is useful in the well-known "downhill" forming technique presently employed in the manufacture of metal tubing from a flat strip of metal stock. The apparatus may be readily adjusted to cause the relatively flat strip of stock being formed to enter the forming section of the mill at the desired angle and thereby militate against undesirable stretching of the metal which might otherwise occur. It will be appreciated that the apparatus, being adjustable, will accommodate any downhill slope required for optimum forming conditions.

From the above description, it will be manifest that a relatively simple structure has been produced to provide for universal adaptation of a tube mill to receive a large variety of strip stock. A wide range of strip thicknesses and widths may be employed by making minor adjustments to the mechanism hereinbefore described.

In accordance with the provisions of the patent statutes, I have explained the principle and mode of operation of my invention and have illustrated and described what I now consider to represent its best embodiment. However, I desire to have it understood that, within the scope of the appended claims, the invention may be practiced otherwise than as specifically illustrated and described.

What is claimed is:

1. In a universal apparatus for forming from a continuous flat strip of metal a tube of a predetermined selected diameter, wherein the flat strip is caused to be moved along a predetermined path and formed from the flat strip into an annular cross-section; said apparatus including an entry table for feeding the strip to a forming section comprising an elongate base frame, a plurality of spaced rolls for supporting the strip and means for preliminarily bending said strip, rotatably mounted on said frame, means for pivotally mounting one end of said base frame, and means for effecting selective vertical movement of the other end of said base frame.

2. In a universal apparatus for forming from a continuous flat strip of metal a tube of a predetermined selected diameter, wherein the flat strip is caused to be moved along a predetermined path and formed from the flat strip into an annular cross-section; said apparatus including an entry table for feeding the strip to a forming section comprising an elongate base frame, a plurality of spaced rolls for supporting the strip and means for preliminarily bending the strip, rotatably mounted on said frame, means for pivotally mounting one end of said base frame, and pressure fluid actuated means selectively raising and lowering the other end of said base frame.

3. In a universal apparatus for forming from a continuous flat strip of metal a tube of a predetermined selected diameter, wherein the flat strip is caused to be moved along a predetermined path and formed from the flat strip into an annular cross-section; said apparatus including an entry table for feeding the strip to a forming section comprising an elongate base frame, a plurality of spaced rolls for supporting the strip and means for preliminarily bending the strip, rotatably mounted on said frame, means for pivotally mounting one end of said base frame, and piston and cylinder means communicating with a source of pressure fluid for controlling selec-

10

tive upward and downward movement of the other end of said base frame.

4. The invention defined in claim 1 including rack and pinion means for maintaining alignment of said base frame during vertical movement of said other end.
